(57) **CLAIM**

The ornamental design for a pan-tilt-zoom camera as shown and described.

DESCRIPTION

FIG. 1 is a front view of a pan-tilt-zoom camera;
FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a top, rear and left side perspective view thereof;
and,
FIG. 8 is a top, front and left side perspective view thereof,
shown in condition of use.
The broken lines and the faded areas depict portions of the pan-tilt-zoom camera in which the design is embodied that form no part of the claimed design.
